UNITED STATES PATENT OFFICE

110,877

DESIGN FOR A BOX COVER

James Quartz, Newton, Mass.

Application February 12, 1938, Serial No. 75,112

Term of patent 14 years

To all whom it may concern:

Be it known that I, James Quartz, a citizen of the United States, residing at 17 Washington Street, Newton, in the county of Middlesex and Commonwealth of Massachusetts, have invented a new, original, and ornamental Design for a Box Cover, of which the following is a specification, reference being had to the accompanying drawing, forming a part thereof.

Fig. 1 is a top plan view of a box cover showing my new design; and

Fig. 2 is a side elevation thereof.

I claim:

The ornamental design for a box cover, as shown.

JAMES QUARTZ.
